ARROW

Paul E. Klopsteg, Evanston, Ill.

Application September 29, 1939, Serial No. 297,145

3 Claims. (Cl. 273—106.5)

The customary way to apply a metallic point or pile to a wooden arrow is to provide a cylindrical, reduced end portion to receive the tubular pile. The pile is forced onto the reduced end of the arrow until it abuts the shoulder formed at the juncture of the main body of the arrow with the reduced end. The outer diameter of the pile is exactly equal to the diameter of the arrow so that the entire length of the arrow is of uniform diameter.

If an arrow of this type strikes a hard object, the arrow will break, particularly if the blow is a glancing one, or at least the pile will be forced sharply against the shoulder on the shaft with the result that the shaft is upset at the shoulder causing the arrow to lose its accuracy in flight.

My invention provides a new form of arrow pile which substantially eliminates the possibility of breakage, or of impacting when the arrow strikes a hard object. It also has the advantage that each time the arrow strikes, the pile is more firmly seated on the shaft.

Other objects and advantages of my improved arrow pile include ease of manufacture and application to an arrow shaft, light-weight, and the facility with which arrows employing the new type of pile may be matched in weight and balance.

Further objects and advantages will become apparent as the disclosure proceeds and the description is read in conjunction with the accompanying drawing, in which—

Fig. 1 is a fragmentary view showing a self-arrow equipped with a conventional type of pile, and showing further, the damage which is done to the arrow by impacting;

Fig. 2 is a corresponding view of an arrow equipped with my improved form of pile, a quarter section of the arrow being cut away to better illustrate the manner in which the pile is joined to the arrow shaft;

Fig. 3 is an end elevational view of the arrow shown in Fig. 2;

Fig. 4 shows an arrow provided with a hunting point that is applied to the arrow shaft in accordance with the teachings of this invention;

Fig. 5 is a side, elevational view of the hunting point shown in Fig. 4; and

Fig. 6 shows another way in which a hunting point may be fixed to the arrow shaft within the scope of this invention.

Most arrows used for tournament play are equipped with hard wood footings at the head of the arrow in order to strengthen the arrow against breakage and impacting. But even with

footings of this kind, breakage and impacting are common.

Although my improved form of pile may be used with arrows equipped with hard wood footings as well as arrows which are not so made (this latter type being known as "self" arrows), the footing is not necessary when my improved pile is used, because of the manner in which the pile protects the shaft. This can best be understood by referring first to Fig. 1, in which a conventional arrow is shown at 10 having a reduced end portion 11 of cylindrical form which produces a shoulder 12 at the juncture of the body of the shaft with the reduced end portion. The pile, generally designated 13, is tubular in form having a sleeve portion 14 which telescopes over the reduced end 11 and abuts the shoulder 12. The tip of the pile 15 is integral with the sleeve portion 14 of the pile.

It is obvious that when an arrow of this type strikes a hard object with a glancing blow, forces are set up at the shoulder 12 which, by reason of the reduced diameter of the shaft at this point and the lever action which takes place, is very likely to break the arrow at or near the shoulder 12. Even if the arrow does not break, and particularly if the blow is head-on, the arrow is usually damaged by reason of the pile being forced against the shoulder 12, causing the wood immediately adjacent the shoulder to be impacted, as indicated at 16.

To overcome this difficulty, I taper the end of the arrow as indicated at 17 and apply a pile which is reamed out with a corresponding taper, as shown in Fig. 2. Preferably a Morse "0" taper (.05208/1) is used for the mating tapered surfaces 17 and the inside diameter of the pile at its rear end 18 is such that when the pile is driven onto the tapered end 19 of the shaft, a small clearance 22 is left between the end of the shaft and the tip of the pile. The exterior face 20 of the pile has a diameter equal to that of the shaft so that it forms a continuation of its surface.

Preferably the clearance 22 between the end of the shaft and the tip 15 of the pile is such that the pile cannot be driven onto the reduced end 19 of the shaft more than an amount which the reduced end 18 of the pile can stand without breakage.

The pile is preferably secured to the arrow shaft by a suitable cement such as Cenco-Sealstix cement, made by the Central Scientific Company of Chicago, Illinois. If desired, the inner face of the pile or a portion of it, may be knurled, as in-

dicated at 23, to firmly grip the shaft and assist in holding the pile in place.

Slight adjustments in the weight of the arrow may be made by turning off suitable portions from the end 18 of the pile. In other words, the length of the pile may be readily varied to provide accurate adjustment of weight.

When an arrow equipped with my improved pile strikes a hard object, the blow is taken over the entire tapered surface of the pile. There are, therefore, no localized stresses and the danger of breakage is substantially eliminated. Furthermore, there is no fulcrum about which high stresses can be set up in the arrow.

The pile is preferably made of brass, or steel, is approximately one-half inch long, with the thickness of the shell at the rear end tapering to approximately .003 to .005 of an inch.

In Figs. 4 and 5, an adaptation of the same principles to a hunting point is shown. The point consists of a spearhead 24 having a tang 25 adapted to be received by a slit 26 in the end of the arrow shaft 21. The end of the shaft is tapered as at 27 and preferably a Morse "0" taper is used, as before.

The tang 25 of the hunting point is held in place by a ferrule 28 which is taper reamed, as indicated at 29 to the same pitch as the tapered surface 27 on the shaft, and the end of the ferrule is flattened, as shown at 30, and provided with an opening to receive the tang of the hunting point. The ferrule 28 is applied to the shaft with cement, as before, and preferably the point 24 is spot-welded or soldered to the ferrule 28 at 31. Obviously whenever the arrow strikes an object, the rearward force applied to the ferrule 28 through the point 24 tends to tighten the grip of the tapered end of the shaft 21 on the tang 25.

The ferrule may, if desired, be made from a bullet jacket 32, as shown in Fig. 6. The jacket is slotted, as shown at 33, to receive the blade 24, and the tang 25 is received as before by a slit 26 in the end of the shaft. If desired, the blade may be spot-welded or soldered to the jacket at 34. The blade in addition to transmitting rearward forces through the soldered or welded connection 24, also transmits these forces to the jacket 32 at the rearward end 35 of the slot 33.

The depth of the slit 26 in the forms of the invention shown in Figs. 5 and 6 is preferably such that the tang 25 will strike the bottom of the slit before excessive stresses are applied to the rear end 18 of the ferrule, thus insuring that the ferrule will not split when the arrow strikes an extremely hard object.

All of the forms of the invention shown are suitable for mass production work and arrows may be quickly matched by turning off desired amounts from the rear ends of the piles or ferrules. Arrows made in accordance with this invention have greatly increased life, and are no more expensive to make than those now commonly used.

What I claim is:

1. An arrow including a cylindrical shaft of substantially uniform diameter having a slightly tapered head and a point for the arrow comprising a body portion having an outer cylindrical surface of substantially the same diameter as the shaft, and an inner tapered surface mating with the tapered head of the shaft, the tapered inner surface of the body constituting substantially the sole force transmitting surface between the point and the shaft, the arrangement being such that the outer surface of the point forms a continuation of the cylindrical surface of the shaft to maintain the accuracy and flight characteristics of the arrow at a maximum, and whereby the force of the arrow striking a hard object merely causes the point to be driven further onto the tapered head of the shaft.
2. An arrow including a cylindrical shaft of substantially uniform diameter having a slightly tapered head with a longitudinal slit, and a point for the arrow comprising a body portion having an outer cylindrical surface of substantially the same diameter as the shaft, and a tapered inner surface mating with the tapered head of the shaft, a blade having a tang extending through the body portion of the point into the slit, the tang being rigid with the body portion and of such length that the end thereof is normally withheld from contact with the shaft, the tapered inner surface of the body constituting the sole force transmitting surface between the point and the arrow shaft, the arrangement being such that the outer surface of the point forms a continuation of the cylindrical surface of the shaft to maintain the accuracy and flight characteristics of the arrow at a maximum, and whereby the force of the arrow striking a hard object merely causes the point to be driven further onto the tapered head of the shaft.
3. An arrow including a cylindrical shaft of substantially uniform diameter having a slightly tapered head, and a point for the arrow comprising a hollow body portion closed at its outer end and having an outer cylindrical surface of substantially the same diameter as the shaft, and an inner tapered surface mating with the tapered head of the shaft and withholding the extremity of the shaft from contact with the outer end of the body portion, the tapered inner surface of the body constituting substantially the sole force transmitting surface between the point and the arrow shaft, the arrangement being such that the outer surface of the point forms a continuation of the cylindrical surface of the shaft to maintain the accuracy and flight characteristics of the arrow at a maximum, and whereby the force of the arrow striking a hard object merely causes the point to be driven further onto the tapered head of the shaft.

PAUL E. KLOPSTEG.
